RAILWAY TRAFFIC CONTROLLING
APPARATUS

James J. Vanhorn, Swissvale, Pa., assignor to The
Union Switch & Signal Company, Swissvale,
Pa., a corporation of Pennsylvania

Application February 24, 1938, Serial No. 192,271

18 Claims. (Cl. 246—3)

My invention relates to railway traffic controlling apparatus, and particularly to apparatus for use in connection with remote control systems for railways. In systems of this character, it is customary to govern wayside signals and track switches from a remote control point, usually the dispatcher's office, and to transmit to the point of control indications of the positions of the various signals in order to keep the operator informed as to the signal indications displayed.

A feature of my invention is the provision of novel and improved remote controlled apparatus for reverse signaling, that is, signaling to permit movements over a stretch of railway track against the normal direction of traffic. Another feature of the invention is the provision of apparatus for governing semi-automatic and manual block signals through the medium of a single control unit, depending upon the track route set up, selection between a clear and a permissive manual block signal being also effected according to the traffic condition of the stretch of track in advance of the signals. A still further feature of the invention is the provision of means to indicate at a remote office station the clear and permissive positions of a signal when it functions as a manual block signal, as well as to indicate the positions of the signal when it functions as a semi-automatic signal. Again, a feature of my invention is the provision of means in centralized traffic control systems of the type here involved for protection against a "hidden lockout" condition. Also, a feature of the invention is the use of the usual "call-on" signal control apparatus for governing manual block signals. Other features and advantages of my invention will appear as the specification progresses.

I shall describe one form of apparatus embodying my invention, and shall then point out the novel features thereof in claims.

Referring to the accompanying drawings, Figs. 1a and 1b, when placed with Fig. 1b at the right of Fig. 1a, are a diagrammatic view of one form of apparatus embodying my invention applied to a stretch of double track railway. Figs. 2a and 2b are diagrammatic views of remote controlled apparatus for governing the relays and circuits of Figs. 1a and 1b. Fig. 3 is a diagrammatic view of indication apparatus for indicating at the office station the position of certain of the wayside signals of Fig. 1a. Figs. 4 and 5 are diagrammatic views of the operating circuits of certain of the signals of Fig. 1a. In each of the several views, similar reference characters refer to similar parts.

Referring to Figs. 1a and 1b, the lineagraph at the top of the drawings illustrates a stretch of double track railway of which EB and WB are the eastbound and westbound tracks, respectively. Two crossovers 3C and 5C are provided at a 5 location A1 near the west end of this stretch of railway for changing of trains from one track to the other. Likewise, at a location A2 near the east end of the stretch, two crossovers 7C and 9C are provided. The track switches of these four 10 crossovers would be preferably power operated by standard switch operating mechanisms (not shown), such mechanisms being controlled from a central office station, to be referred to more fully hereinafter. The control of such power 15 operated switch mechanisms is omitted from the drawings as it is not required to illustrate the present invention. The tracks EB and WB are preferably arranged into track sections and provided with automatic signals for governing traffic 20 in the normal direction, and the westbound track WB is provided with apparatus according to my invention for reverse signaling. This signaling condition is indicated by the double arrows placed on the westbound track WB and by the single 25 arrow placed on the eastbound track TB. The automatic signals provided for the tracks EB and WB between locations A1 and A2 would be in accordance with standard practice and are also not shown for the sake of simplicity, since 30 they are not required to illustrate the present invention. At location A1, two detector track sections 3T and 5T are formed for the tracks EB and WB, respectively, these track sections extending to the limits of the crossovers 3C and 5C. 35 Also, at location A2, two detector track sections 7T and 9T extending to the limits of the crossovers 7C and 9C are provided. Each of these four track sections is provided with the usual track circuit which includes a track relay. These 40 track relays for the sections 3T, 5T, 7T and 9T are indicated by the reference character R with a prefix corresponding to the track section, and the association of a track relay with its track section is indicated by a dash line.

Before proceeding further with the description, it should be pointed out that the contact fingers of these track relays, as well as the contact fingers of other relays to be described later in the specification, are in most instances shown remote from the winding of the relay. In each such case, the contact finger is identified by the reference character corresponding to that of the relay by which it is operated, and the contact finger is shown in the position corresponding to 45 50 55

the normal position of the relay. It should also be pointed out at this time that the track switches of the crossovers 3C, 5C, 7C and 9C would have connected therewith switch circuit controllers for opening and closing contacts according to the position of the crossovers. In order to simplify the drawings, the contacts of such switch circuit controllers only are shown, and the contacts are given as a reference character the numeral corresponding to that of the associated crossover, plus the letter N or R, according to whether the contact is closed at the normal or the reverse position of the crossover, and in addition the contact bears a distinguishing numeral. For example, the contact 5N-20 of Fig. 1a is actuated by the crossover 5C and is closed at the normal position of the crossover, and the contact 3R-21 is actuated by the crossover 3C and is closed at the reverse position of crossover 3C.

At location A1, eastbound movements are governed by signals R2 and R4, and westbound movements are governed by signals L2 and L4. Signals R6 and R8 govern eastbound movements at location A2, and signals L6 and L8 govern westbound movements at location A2. The signals R2, L4, R6 and L8 are in each case provided with two signal mechanisms mounted on the same mast, the top and bottom signal mechanisms being identified as A and B, respectively. Since, as pointed out hereinbefore, the tracks EB and WB are equipped with automatic signals, the signals at locations A1 and A2 would be semi-automatic signals controlled in part by the automatic signal apparatus and in part by a remote control or centralized traffic control system, to be later described. According to my invention, the signals RB2 and R4 are also controlled by the remote control system as manual block signals to direct train movements against the normal direction of traffic on the track WB. Looking at location A1 and assuming the crossover 5C to be in its reverse position, the signal R4 would function as a semi-automatic signal to direct a movement east on the track EB, but, if the crossover 5C is normal, the signal R4 would be used as a manual block signal to direct movement east over the westbound track WB. In a similar manner, the signal RB2 would at times function as a semi-automatic signal, and at other times as a manual block signal, depending upon the route set up by the crossovers 3C and 5C.

The type of wayside signal is immaterial, and standard three-position color light signals may be used.

The operating circuits for each of these signals are governed by a signal control relay, each signal control relay being identified by the reference character H with a prefix corresponding to the reference character of the signal it controls. Looking at signal R2, for example, the operating circuits for the top signal mechanism A are governed by a signal control relay RA2H, and the operating circuits for the bottom signal mechanism B are governed by a relay RB2H. It will be understood, of course, that the position of signal RA2 is further governed by the usual line circuit control responsive to traffic conditions in advance of the signal. In a similar fashion, the signal control relays R4H, LA4H, LB4H and L2H govern the respective signals at location A1. At location A2, the signal control relays LA8H and L6H govern the operating circuits for the respective signals LA8 and L6. The signal control relays for the other signals at location A2 are not shown, in order to not unduly complicate

the drawings since such relays are not involved in the instant invention.

In order that the signals RB2 and R4 at location A1 may be used as manual block signals, the operating circuits of the respective signals are also governed by the relays RB2D and R4D, respectively. One form of operating circuits that may be used for signal R2 is illustrated in Fig. 4. When the control relays RA2H and RB2H are deenergized, closing the respective back contacts 196 and 197, the lamps 198 and 199 of the respective mechanisms A and B of signal R2 are illuminated to display a stop signal. With relay RA2H and the usual line relay 201 picked up, closing front contacts 200 and 202, respectively, and with relay RB2H released, the green lamp 203 of mechanism A and the red lamp 199 of mechanism B are illuminated to display a clear semi-automatic signal. If the traffic conditions are such that line relay 201 is down, closing back contact 204, then the yellow lamp 205 is illuminated in place of the green lamp 203 to display a permissive semi-automatic signal. With control relay RB2H and relay RB2D picked up, closing the respective front contacts 206 and 207, and with relay RA2H released, then the green lamp 208 of mechanism B is illuminated under the red lamp 198 to display a clear manual block signal. Again, with relay RB2H picked up and relay RB2D released, closing its back contact 209, the yellow lamp 210 of mechanism B is illuminated under the red lamp 198 to display a permissive manual block signal. This last arrangement would also be used to display a semi-automatic signal, distinction between a permissive manual block signal and a semi-automatic signal by the mechanism B of signal R2 being determined by the position of the crossovers 3C and 5C.

Looking at Fig. 5, when the control relay R4H and relay R4D are both picked up, closing the respective front contacts 211 and 212, the green lamp 213 of signal R4 is illuminated to display a clear manual block signal. If relay R4D is released, closing its back contact 214, and relay R4H is picked up, then the yellow lamp 215 of signal R4 is illuminated to display a permissive manual block signal or a permissive semi-automatic signal, as determined by the position of the crossover 5C. The red lamp 216 of signal R4 is normally illuminated by virtue of the operating circuit completed at back contact 217 of relay R4H. The operating circuits for the other signals are not shown, and it is deemed sufficient to point out that when a signal control relay is released the associated signal displays a stop signal, and when the signal control relay is picked up the signal displays a proceed signal.

The stop position of each of the wayside signals is checked through the medium of a relay identified by the reference characters GP with a prefix corresponding to the signal. These checking relays are normally energized over back contacts of the associated signal control relays. Looking at relay R2GP for signal R2 (Fig. 1a), the circuit involved extends from terminal X of any convenient source of current, such as a battery not shown, back contact 22 of signal control relay RB2H, back contact 23 of signal control relay RA2H, winding of relay R2GP, and to terminal Y of the current source. The checking relays R4GP, L4GP and L2GP at location A1 are each normally energized over a circuit similar to that described for relay R2GP, as will be understood by an inspection of Fig. 1a. The checking relays GP for the signals at location A2

are omitted from the drawings since they are not involved in the present invention.

In order to provide reverse signaling for the track WB, the apparatus at location A1 is associated with the apparatus at location A2 by a traffic locking circuit, and which circuit includes a directional relay and a directional repeater relay, as well as a current source at each location. This traffic locking circuit is completed between the two locations over line wires 24 and 25 in which there are interposed front contacts of the track relays of the intervening track sections for the track WB, such front contacts being illustrated by the TR contacts 98 and 99 of Fig. 1a. That is to say, contacts TR-98 and TR-99 are open as long as the track WB between the locations A1 and A2 is occupied. The traffic locking circuit is also governed by circuit networks at each of the two locations, which networks will be taken up and referred to when the operation of the apparatus is explained. At this point, it is sufficient to note that this traffic locking circuit is conditioned by the network, when an east-bound movement from location A1 on track WB is to be made, to energize a directional relay 4F at location A1 by current supplied from a battery 26 at location A2, the winding of a repeater relay 4FP at location A2 being serially interposed in the circuit. When a westbound movement is to be made from location A2 over track WB, the traffic locking circuit is conditioned by the network to energize a directional relay 8F at location A2 by current supplied from a battery 21 at location A1, a repeater relay 8FP at location A1 being serially interposed in the circuit.

Two traffic following stick relays 4FS and 8FS placed at locations A1 and A2, respectively, are associated with the traffic locking circuit for protection against a "hidden lockout" condition of the remote control apparatus as well as to effect a permissive manual block signal for the signals RB2 and R4 in a manner to later be described. Looking at the traffic following relay 4FS, for example, a pick-up circuit is formed for this relay when the associated directional relay 4F is picked up and a train enters either of the track sections 3T or 5T. This pick-up circuit comprises a front contact 4F-100, contact 5N-102, and two branch paths one of which includes back contact 5TR-101 and the other of which includes back contact 3TR-104 and contact 3R-103. With the traffic following relay 4FS picked up, it is retained energized subsequent to the release of the directional relay 4F in a manner to later appear over a simple stick circuit including back contact 4F-105. The traffic following relay 8FS at location A2 is controlled by circuits governed by the associated directional relay 8F, the track relays 7TR and 9TR, and the position of the crossovers 9C and 7C, and which circuits are similar to those described for relay 4FS and the description need not be repeated in detail.

Referring now to Figs. 2a and 2b as well as to Figs. 1a and 1b, the apparatus at the locations A1 and A2 is controlled from a remote office station through the medium of remote or code controlled stick relays HS, there being a remote controlled relay HS for each wayside signal. The relationship between a remote controlled relay HS and the signal it controls is indicated by providing each HS relay with a prefix corresponding to the signal it governs. The system for controlling the HS relays from a remote office station may be a direct wire system using a line wire for each relay, or it may be a code system using a single

two-wire line circuit for controlling all the relays. I shall assume that the remote control or centralized traffic control system to be used is the time code system described and claimed in the United States application for Letters Patent Serial No. 600,786, filed March 23, 1932, by L. V. Lewis for Remote control systems, and to which application reference is made for a full understanding of such systems. It is sufficient for the present application to point out that two line coding storage units 1-2 and 3-4 shown conventionally in Fig. 2a and Fig. 2b are located at each field station adjacent the respective locations A1 and A2, and are selectively operated in response to code signals sent from a central office station (not shown). When a storage unit is operated, positive energy is made to appear at the terminals 4, 5, 6 and 7 of the unit, according to the code signal operating the unit. Positive energy is applied to the terminals 4 and 5 of the operated unit only during the reception of the code signal to pick up the selected HS relay. Positive energy remains on the terminal 6 of the operated unit subsequent to the sending of the code signal for holding the selected HS relay energized over a stick circuit. Two relays 2USR and 4USR are provided at the location A1 and are operated by the coding storage units when the code signal transmitted causes positive energy to appear at the terminal 7 of the associated unit. The relays 2USR and 4USR are selected by the operator when he desires to provide the usual "call-on" signal in connection with movements in the normal direction of traffic and when he desires to operate the signal RB2 or R4 as a manual block signal. At location A2, only the code controlled relays L6HS and L8HS for the signals L6 and L8 are shown since these two remote or code controlled relays and their control circuits are sufficient for a full understanding of my invention.

Fig. 3 diagrammatically discloses apparatus for indicating at the central office station the position of the signals at location A1, that part of the apparatus included in the centralized traffic control system being indicated in Fig. 3 by dash lines between the field station and the office station, since this part of the apparatus is not required for illustrating my invention and may be in accordance with that described in the aforementioned Lewis application Serial No. 600,786. When signals R2 and L2 are at stop so that relays R2GP and L2GP are picked up, closing front contacts 28 and 29, respectively, the lamp 30 at the office station is illuminated to indicate the stop position of these two signals. With either signal mechanism RB2 or RA2 of signal R2 operated to a proceed position and relay R2GP de-energized, closing back contact 31, the lamp 32 at the office station is illuminated to indicate the proceed position of signal R2. Again, when relay L2GP is deenergized, closing its back contact 33 in response to the signal L2 being operated to a proceed position, the lamp 34 at the office station is illuminated. In the event the crossover 3C is in its reverse position and crossover 5C is normal, and relays RB2D and RB2H are energized in a manner to be later described to clear signal RB2 as a manual block signal, a circuit is formed at the field station including back contact 31 of relay R2GP, contact 3R-35, contact 5N-36, and front contact 37 of relay RB2D, and the lamp 38 at the office station is illuminated to indicate the clear position of signal RB2 as a manual block signal. The lamp 32 will also be

illuminated due to the closing of back contact R2GP-31. Thus, the lamp 32 will indicate that the signal RB2 is operated and the lamp 38 will indicate that a clear manual block signal is displayed by signal RB2. If, under this track route, the relay RB2D remains deenergized and relay RB2H is energized so that a permissive manual block signal is displayed at signal RB2, a circuit is formed at the field station, the same as traced 5 above up to contact 5N-36, and thence over back contact 39 of relay RD2D, and the lamp 40 at the office station is illuminated. This time the lamp 32 will indicate that signal RB2 is operated and the lamp 40 will indicate that a permissive manual block signal is displayed. The lamp 43 is illuminated by means of a circuit completed at front contact 41 of relay R4GP and front contact 42 of relay L4GP at the field station to indicate to the operator the stop position of signals R4 and L4. With the crossover 5C in its reverse position and relay R4H energized to operate signal R4 as a semi-automatic signal, the back contact 44 of relay R4GP is closed and the lamp 45 at the office station is illuminated. Again, if relay LA4H 10 or LB4H is energized and the signal L4 is operated, back contact 46 of relay L4GP is closed and the lamp 47 at the office station is illuminated. In the event the crossover 5C is normal and relay R4D is energized along with relay R4H to clear 15 the signal R4 as a manual block signal, a circuit including back contact R4GP-44, contact 5N-48 and front contact R4D-49 is completed, with the result that lamp 50 at the office station is illuminated to indicate the clear position of the 20 manual block signal R4. The lamp 45 will also be illuminated since back contact R4GP-44 is closed. Thus, lamp 45 will indicate that signal R4 is operated and lamp 50 will indicate that a clear manual block signal is displayed at signal 25 R4. If relay R4D remains deenergized so that a permissive manual block signal is displayed at signal R4, the field station connection is completed at back contact R4D-51, and the lamp 52 at the office station is illuminated to indicate the 30 permissive position of the manual block signal, the lamp 45 being also illuminated. When the traffic following stick relay 4FS associated with the traffic locking circuit at location A1 is picked up in response to a train moving to track WB at 35 location A1 in a manner to later be described, the closing of front contact 53 of relay 4FS completes a circuit connection at the field station for causing the lamp 54 at the office station to be illuminated to indicate to the operator that an 40 eastbound movement over track WB is being made. The indication apparatus associated with the location A2 for indicating the position of the signals at location A2 is omitted since it forms no part of my present invention.

To described the operation of the apparatus, I shall first point out in step-by-step fashion the operations necessary to operate the signal RA2 as a semi-automatic signal, it being assumed 45 that the circuits and relays, as well as the crossovers are normally in the positions illustrated in the drawings. The operator at the office station sends the necessary code signal to operate the unit 1-2 at location A1 (Fig. 2a) so that positive energy appears at terminals 5 and 6 of that unit.

With positive energy applied to terminal 5 of unit 1-2 of Fig. 2a, the relay R2HS is picked up over contact 3N-62 in multiple with front contact L4GP-63 and back contact 3FP-64, winding of relay R2HS, contact 5N-65 and to the negative 50 terminal Y. Subsequent to the sending of the

code signal, the relay R2HS is retained energized by a stick circuit extending from terminal 6 over resistance 61, front contact 66 of track relay 3TR, contact 3N-67, back contact 68 of the opposing code relay L2HS, front contact 69 and winding of relay R2HS, contact 5N-65 and terminal Y. With the code controlled relay R2HS thus selected, the signal control relay RA2H receives current from terminal X (see Fig. 1a) over back contact L2HS-70, contacts 5N-71 and 3N-72, 5 front contact 73 of relay R2HS, contact 3N-74, front contact 3TR-75, winding of relay RA2H, contact R2HS-76 and to terminal Y, and the relay RA2H is picked up. As explained hereinbefore, the picking up of relay RA2H causes signal RA2 to be operated to a proceed position. It is to be understood, of course, that signal control relay RA2H would also be controlled by approach locking circuits of any desired form as well as by the apparatus of the automatic signal system for track EB. When the relay RA2H picks up, opening back contact 23 interposed in the circuit of relay R2GP, relay R2GP is released closing its back contact 31 and the lamp 32 (see Fig. 3) at the office station is illuminated. In 25 case the crossovers 3C and 5C are both set at their reverse positions prior to the code controlled relay R2HS being selected, the signal control relay RB2H is picked up to operate the signal RB2 as a semi-automatic signal. Looking at Fig. 1a, the circuit for relay RB2H comprises terminal X, back contact L2HS-70, contacts 5R-77 and 3R-78, front contact R2HS-73, contact 3R-79, back contact 80 of relay RA2H, winding of relay RB2H, front contact R2HS-76 and terminal Y. 30 With relay RB2H energized, the operating circuit for lamp 210 of signal RB2 is closed and the signal is operated to a proceed position, this position being indicated at the office station by means of lamp 32, in the manner already explained. 35

It should be explained at this point that to operate signal RB2 as a "call-on" signal when the crossovers 3C and 5C are normal the operator would modify the code signal operating unit 1-2 at location A1 (Fig. 2a) so as to not only select 40 relay R2HS, in the manner explained above, but positive energy would also appear at terminal 7 of unit 1-2 and relay 2USR would be picked up over a simple circuit and then retained energized over a stick circuit involving back contact 81 of 45 relay L2HS and front contact 82 of relay R2HS. With both relays R2HS and 2USR picked up, the relay RB2H receives current over a circuit including the elements: terminal X, back contact L2HS-70, contacts 5N-71 and 3N-72, front 50 contact R2HS-73, contact 3N-83, front contact 2USR-84, and thence as previously traced, the relay RA2H not responding to this circuit due to 55 some traffic conditions. Under these circumstances, the signal RB2 would display the usual 60 "call-on" signal to permit a train to pass the signal R2, notwithstanding some unusual traffic condition.

In the event the crossover 5C is reversed and signal R4 is to be operated as a semi-automatic 65 signal, the operator transmits a code signal to select relay R4HS, the code signal operating the unit 3-4 at location A1 (Fig. 2a) to cause positive energy to appear at the terminals 5 and 6 of that unit. The code controlled relay R4HS is 70 picked up by current flowing from terminal 5 of unit 3-4 over front contact L2GP-55, contact 5R-56, winding of relay R4HS, contact 3N-87 and terminal Y. The stick circuit for relay R4HS 75 extends from terminal 6 of the associated unit

3-4 over resistance 57, contact 5R-58, back contact 59 of relay L2HS, back contact 60 of relay L4HS, front contact 94 and winding of relay R4HS, contact 3N-87, and thence to the terminal Y. With relay R4HS selected, the signal control relay R4H is provided with a pick-up circuit including terminal X (see Fig. 1a), back contact L2HS-70, contact 5R-71, contact 3N-95, front contact 96 of relay R4HS, winding of relay R4H, front contact 97 of relay R4HS and terminal Y. With relay R4H energized, the lamp 215 (Fig. 5) of signal R4 is illuminated to display a proceed semi-automatic signal. This position of signal R4 is indicated at the office station by lamp 45 (Fig. 3) being illuminated, since the relay R4GP is released, closing back contact 44 when relay R4H is picked up.

The operation thus far is in accordance with standard practice, and it is believed the above description for the operation of signals R2 and R4 as semi-automatic signals will serve to illustrate the control of the other signals at location A1 as well as the semi-automatic control of the signals at location A2, except as the operation of signals L6 and L8 will be referred to hereinafter.

I shall next describe the steps involved in controlling the signal R4 as a manual block signal, the crossovers 3C and 5C being normal for a train to move east over the track WB. The operator transmits a code signal necessary to operate the unit 3-4 at location A1 (Fig. 2a) to select the relay R4HS and also the relay 4USR. The pick-up circuit for relay R4HS differs from that used when signal R4 functions as a semi-automatic signal in that it now includes terminal 5, contact 5N-85 and back contact 86 of relay 8FP. It is to be noted that back contact 8FP-86 prevents the relay R4HS from responding to the code signal in the event that the traffic locking circuit is conditioned for westbound traffic and the relay 8FP is picked up in a manner to be shortly described. The stick circuit for relay R4HS is now formed over terminal 6, resistor 57, front contact 5TR-106, front contact 107 of the directional relay 4F of the traffic locking circuit and contact 5N-108, or it may be formed over a path including front contact 109 of the traffic following relay 4FS. Thus, to retain relay R4HS energized after completion of the code signal, it is necessary that the traffic locking circuit be conditioned to energize the directional relay 4F. The relay 4USR responds to the code signal, since positive energy appears at the terminal 7 of the associated unit 3-4, and the relay 4USR is then retained energized over its stick circuit including back contact 111 of relay L4HS and front contact 110 of relay R4HS.

When the code controlled relay R4HS is first picked up by the code signal, the traffic locking circuit is conditioned for energizing the directional relay 4F and the repeater relay 4FP, to select the eastbound direction of traffic from location A1 to location A2 over the track WB. Starting from battery 26 at location A2 (Fig. 1b), the traffic locking circuit can be traced over winding of repeater relay 4FP, back contact 8F-88, back contact 8FS-89, contact 9N-112 in multiple with back contact L6HS-194 and front contact 7TR-91, back contact L8HS-92, front contact 9TR-93, line wire 24 over contact TR-99 of the intervening track relays (see Fig. 1a), front contact 5TR-113, front contact 114 of relay R4HS, contact 5N-20, winding of relay 4F, contact 5N-181, front contact R4HS-116, front contact 5TR-117, line wire 25 over the contact TR-99 of

the intervening track relays, front contact 9TR-118 (Fig. 1b), back contact L8HS-119, contact 9N-120 in multiple with front contact 7TR-174 and back contact L6HS-195, back contact 8FS-121, back contact 8F-122, and to battery 26. Relays 4FP and 4F are now picked up. It will be understood, of course, that this traffic locking circuit will also be governed by the usual approach locking circuits at locations A1 and A2. The picking up of relay 4FP prevents the relays L6HS and L8HS from responding to a code signal to provide an aspect on signals L6 or LA8 for a train movement toward location A2 on track WB due to the fact that back contacts 4FP-123 and 4FP-124 (see Fig. 2b) are interposed in the respective pick-up circuits for these code controlled relays. The picking up of the directional relay 4F closing its front contact 107 completes the stick circuit for the code controlled relay R4HS, as explained above. With both relays R4HS and 4F picked up, the signal control relay R4H is then selected by current flowing from terminal X over front contact 4F-125 (Fig. 1a), back contact L4HS-126, contacts 5N-127 and 3N-95, front contact R4HS-96, winding of relay R4H, and to terminal Y over contact R4HS-97. The next step is to energize the relay R4D, for which a circuit is formed from terminal X over front contact 4F-128, contact 5N-140, contact 3N-129, front contact 4USR-130, front contact R4H-131, winding of relay R4D and terminal Y. As previously explained, when both relays R4H and R4D are picked up, the lamp 213 of signal R4 is illuminated to display a clear manual block signal. Since relay R4GP is released, closing its back contact 44 (see Fig. 3) when the signal R4 is operated, the lamp 50 is illuminated to indicate the clear position of signal R4 as a manual block signal, the lamp 45 being also illuminated to indicate that the signal R4 is operated.

When the train moves past signal R4 into section 5T and shunts track relay 5TR, the traffic locking circuit is opened at front contacts 113 and 117 of relay 5TR so that the directional relay 4F is deenergized and releases at the end of its slow release period. During the interval the relay 5TR is down and relay 4F is up, the traffic following relay 4FS is picked up over back contact 5TR-101 and front contact 4F-100 and is then retained energized by its stick circuit. Since front contact 5TR-106 is interposed in the stick circuit of code controlled relay R4HS, relay R4HS is released before the traffic following relay 4FS picks up to close at front contact 4FS-109 a second path in the stick circuit of relay R4HS. It is to be noted that front contact 5TR-132 and resistance 133 are connected across the winding of relay R4HS, causing the relay R4HS to be slow releasing so as not to release at the end of the code signal before relay 4F is picked up, closing the stick circuit for relay R4HS. With the shunting of track relay 5TR opening front contact 132, the slow release feature of relay R4HS is removed, and the release of relay R4HS in response to the train entering the track section 5T is assured. With the release of relay R4HS the relay 4USR is also released.

The relay 4F remains deenergized and relay 4FS remains energized until the train moves east and vacates the track section 9T at location A2, and the track relays are all picked up to reclose the traffic locking circuit. In the even a second train is to move east over the track WB before the first train vacates the stretch, the operator would transmit a new code signal to select the relays

R4HS and 4USR. The relay R4HS is now retained energized over its stick circuit completed at the front contact 4FS-109. The signal control relay R4H is reenergized in response to the selection of relay R4HS inasmuch as its circuit is prepared at the front contact 4FS-134. Relay R4D, however, is not at this time energized because its circuit remains open at front contact 4F-128. Under this set-up of the controlling relays, the lamp 215 of signal R4 is illuminated to display a permissive manual block signal. Because relay R4D is not energized, the closing of its back contact 51 (see Fig. 3) causes the lamp 52 to be illuminated to indicate the permissive position of the manual block signal R4.

When the crossover 3C is in its reverse position and crossover 5C is normal for a train to move east from location A1 over track WB, the signal RB2 is used as a manual block signal. Under this route condition, the operator, to operate signal RB2, would transmit a code signal to operate unit 1-2 at location A1 (Fig. 2a) and select the relays R2HS and 2USR. The pick-up circuits for relays R2HS and 2USR are the same as previously traced. With relay R2HS picked up, the traffic locking circuit is completed as required to energize the directional relay 4F and the repeater relay 4FP, the circuit network for the traffic locking circuit being the same as previously traced except that at location A1 it includes back contact 135 of relay R4HS, front contact 3TR-136, front contact R2HS-137, contact 3R-21, contact 5N-28, winding of relay 4F, contacts 5N-181 and 3R-115, front contact R2HS-182, front contact 3TR-183 and back contact R4HS-156. With the relay 4F picked up, the stick circuit for relay R2HS is completed, the effective path including front contacts 4F-138 and 3TR-139 and contact 3R-141. At the next step, the signal control relay RB2H is energized, the network for relay RB2H (Fig. 1a) now extending from terminal X over front contact 4F-125, back contact 14HS-126, contacts 5N-127 and 3R-78, front contact R2HS-73, contact 3R-79, back contact 80 of relay RA2H, winding of relay RB2H, front contact R2HS-76 and terminal Y. The next operating step is that of energizing the relay RB2D which now receives current over front contact 4F-128, contacts 5N-140 and 3R-141, front contact 2USR-142, front contact RB2H-143, winding of relay RB2D and to the terminal Y. As previously explained, this setup of relays is effective to cause the lamp 208 of signal RB2 to be operated to display a clear manual block signal. As explained in connection with Fig. 3, this condition causes the lamp 38 at the office station to be illuminated to indicate the clear position of signal RB2 as a manual block signal, the lamp 32 being also illuminated to indicate that signal R2 is operated.

The train, on advancing past the signal RB2 to enter the section 3T, shunts the track relay 3TR, and that relay, upon releasing, opens the traffic locking circuit at front contacts 136 and 183 so that the relay 4F is deenergized and releases at the end of its slow release period. The traffic following relay 4FS is picked up over the circuit including back contact 3TR-104 and front contact 4F-100 in response to the train entering the track section 3T, and is then retained energized by its stick circuit. The relay R2HS is also released in response to the train entering section 3T, since the front contact 3TR-139 is interposed in the stick circuit for relay R2HS. In this connection, it is to be noted

that the relay R2HS is provided with a shunt path across its winding including front contact 3TR-144 and resistance 145, so that the relay R2HS is provided with a slow release characteristic and does not release at the end of the code signal before the relay 4F is picked up. However, when the train enters the section 3T and shunts track relay 3TR, the slow release feature for relay R2HS is removed and relay R2HS is released before relay 4FS picks up to close the stick circuit for relay R2HS over the path including front contact 4FS-146 and contact 3R-147. With relay R2HS released opening its front contact R2HS-82, the relay 2USR is also released.

In order to permit a second train to follow east over track WB before the first train vacates the stretch, the operator must send a new code signal to select the relays R2HS and 2USR. This time, the stick circuit for relay R2HS is formed over the path including front contact 4FS-146 and contact 3R-147. Again, the signal control relay RB2H is picked up, but the relay RB2D remains released since front contact 4F-128 remains open. The lamp 210 of signal RB2 is now operated to display a permissive manual block signal, and the lamp 40 is illuminated at the office station to indicate this permissive position of the signal. It is to be noted that as long as the eastbound train occupies the track WB the fact is indicated at the office station by lamp 54, since the front contact 4FS-53 is closed. It follows from the foregoing discussion that the signals R4 and R2 at location A1 are operated by the remote control system either as semi-automatic signals or as manual block signals, depending upon the route set up.

Returning to the control of the code controlled relay R4HS, it is to be observed that if for some reason relay 4F should fail to pick up to establish the direction of traffic the relay R4HS would release, as energy is applied to the terminal 5 of the unit 3-4 of Fig. 2a only during the reception of the code signal and its stick circuit is open at front contact 4F-107. Likewise, if relay 4FS failed to pick up when the train passes the signal R4, then a subsequent coding of the relay R4HS would be ineffective, since the stick circuit for relay R4HS is open at front contact 4FS-109. Therefore, when relays 4F and 4FS fail to properly operate, the relay R4HS cannot be selected. If relay R4HS was to be selected improperly, although the signal R4 would not be cleared, the operator might overlook that he had coded this particular control and the centralized traffic control system would be rendered ineffective to operate any of the opposing HS relays. A failure of this type, commonly referred to as "hidden lockout", is avoided by virtue of the relays 4F and 4FS controlling the stick circuit of the code controlled relay R4HS. A similar protection is accomplished when the route is set up for signal RB2 to be operated as a manual block signal. This time, the code controlled relay R2HS is not retained energized subsequent to a code signal if the directional relay 4F fails and is not picked up to close the stick circuit of relay R2HS at front contact 4F-138. Also, a second code signal is not effective to select the relay R2HS if the traffic following relay 4FS is not picked up to prepare the stick circuit for relay R2HS. Thus, a "hidden lockout" condition for code relay R2HS is avoided by virtue of the relays 4F and 4FS controlling the stick circuit for relay R2HS.

Starting again with the apparatus in its normal

position, and assuming the signal L8 at location A2 is to be operated for a movement west on the track WB, the operator sends a code signal effective to operate the unit 1-2 at location A2 (Fig. 2b) to energize the code controlled relay L8HS. With positive energy applied to the terminal 5 of unit 1-2 at location A2, the relay L8HS is picked up over a circuit including contact 7N-148 and the back contact 4FP-124. When relay L8HS is first picked up, the traffic locking circuit is conditioned as required to establish westbound traffic by energizing the directional relay 8F and the repeater relay 8FP. To be explicit, the traffic locking circuit now formed extends from battery 27 at location A1 over winding of relay 8FP, back contact 4F-149, back contact 4FS-150, contact 3N-151, back contact R4HS-135, front contact 5TR-113, line wire 24 through the contact TR-98, front contact 9TR-93, front contact L8HS-152, contact 7N-153, winding of relay 8F, contact 7N-154, front contact L8HS-155, front contact 9TR-118, line wire 25 through contact TR-99, front contact 5TR-117, back contact R4HS-156, contact 3N-157, back contact 4FS-158, back contact 4F-159 and to battery 27. With the directional relay 8F thus energized, the stick circuit for relay L8HS is completed at front contact 8F-160 (Fig. 2b), so that the relay L8HS remains energized in response to the code signal. On the next step in the operation, the signal control relay LA8H is picked up (Fig. 1b), its circuit being completed at front contact 8F-161 and front contacts L8HS-162 and L8HS-163, as will be understood from an inspection of Fig. 1b. Relay LA8H on picking up causes the signal L8 to be operated to display a proceed indication.

The train upon advancing past the signal L8 to enter the section 9T shunts the track relay 9TR and the traffic locking circuit is opened at front contacts 93 and 118 of relay 9TR, so that relay 8F is deenergized and releases at the end of its slow release period.

Since the relay 8F is slow releasing, the traffic following relay 8FS is picked up during the interval between the release of the track relay 9TR and the release of the directional relay 8F, the pick-up circuit for relay 8FS being formed at back contact 9TR-167 and front contact 8F-166. Relay 8FS is retained energized subsequent to the release of relay 8F over its stick circuit including the back contact 8F-168. The relays L8HS and LA8H are also both deenergized and released in response to the train entering the section 9T, since front contact 9TR-164 is interposed in the stick circuit of relay L8HS and front contact 9TR-165 is interposed in the circuit for relay LA8H. In this connection, it is to be pointed out that relay L8HS is provided with a shunt path including front contact 9TR-187, so that the relay is slow releasing and does not release during the energizing of the directional relay 8F to close the stick circuit for relay L8HS, the slow release feature is removed when the train enters the section 9T, and release of relay L8HS before the relay 8FS picks up to close at its front contact 169 another path in the stick circuit of relay L8HS, is assured.

To permit a second westbound train to move from location A2 before the first train vacates the stretch, the operator must again transmit a code signal for operating the unit 1-2 at location A2 (Fig. 2b) and selecting the relay L8HS, relay L8HS being now provided with a stick circuit completed at front contact 8FS-169. The

signal control relay LA8H is now energized and picked up by virtue of the circuit completed at front contact 8FS-170 and front contacts L8HS-162 and L8HS-163. With relay LA8H picked up, the signal L8 is again operated to display a proceed indication. It is to be understood, of course, that the signal control relay LA8H will also be governed by apparatus of the automatic signal system in accordance with standard practice.

When the crossover 9C is moved to its reverse position and crossover 7C is normal, the signal L6 would be effective for governing westbound movements over the track WB. Under these conditions, the operator sends a code signal effective to operate unit 3-4 at location A-2 (Fig. 2b) to select the relay L6HS. With relay L6HS picked up in response to positive energy appearing at the terminal 5 of the associated unit 3-4, the traffic locking circuit is conditioned to energize directional relay 8F to establish westbound traffic. The traffic locking circuit is the same as traced in connection with the operation of signal L8, except at location A2 the network now formed includes the following elements from line wire 24 (Fig. 1b): front contact 9TR-93, back contact L8HS-92, front contact 7TR-91, front contact L6HS-193, contact 9R-171, contact 7N-153, winding of relay 8F, contacts 7N-154 and 9R-172, front contact L6HS-173, front contact 7TR-174, back contact L8HS-119 and front contact 9TR-118 to the line wire 25. Directional relay 8F now picks up and completes the stick circuit for the code controlled relay L6HS at front contact 8F-175, contact 9R-188 and front contact 7TR-191 being also interposed in the stick circuit. As the next step, the signal control relay L6H receives current over front contact 8F-161, contacts 9R-176 and 7N-177, as well as the two front contacts 178 and 179 of relay L6HS. Relay L6H on picking up causes the operation of signal L6 to a proceed position.

When the train enters section 7T to shunt track relay 7TR, the traffic locking circuit is opened at front contacts 91 and 174 of relay 7TR, and the directional relay 8F is released, the same as before. Since contact 9R-190 is now closed, the shunting of track relay 7TR to close its back contact 189 completes the pick-up circuit for the traffic following relay 8FS and that relay is picked up during the release period of the directional relay 8F and is then held energized over the stick circuit including back contact 8F-168. The relays L6HS and L6H are both deenergized in response to the train entering the track section 7T, since the stick circuit for relay L6HS is opened at front contact 7TR-191 and relay L6HS upon releasing opens the circuit for relay L6H at front contacts 178 and 179.

To permit a following movement past signal L6 over crossover 9C and to the track WB, the operator sends a new code signal for operating the unit 3-4 at location A2 to energize relay L6HS, relay L6HS being now provided with a stick circuit completed at front contact 8FS-170 and contact 9R-188. With relay L6HS thus selected, the relay L6H is picked up by virtue of the circuit completed at front contact 8FS-170 and the front contacts 178 and 179 of relay L6HS. With relay L6H picked up, the signal L6 is operated to a proceed position.

It is clear that the relays 8F and 8FS function to prevent a "hidden lockout" condition in respect to the relays L6HS and L8HS, in the same manner as described for relays 4F and 4FS in con-

connection with the code controlled relays R2HS and R4HS at location A¹, and the description need not be repeated.

Although I have herein shown and described 5 only one form of apparatus embodying my invention, it is understood that various changes and modifications may be made therein within the scope of the appended claims without departing from the spirit and scope of my invention.

10 Having thus described my invention, what I claim is:

1. Railway traffic controlling apparatus in combination with a stretch of track comprising, a signal at each end of the stretch for governing traffic into the stretch, a remote controlled relay for each signal effective when energized to cause operation of the signal, a traffic locking circuit for the stretch responsive to a train occupying the stretch and including a directional relay at each 15 end of the stretch, means governed by each remote controlled relay when operated to condition the traffic locking circuit for energizing the directional relay at the same end of the stretch, a stick circuit for each remote controlled relay 20 including a front contact of the associated directional relay, a traffic following relay at each end of the stretch effectively energized in response to a train entering the stretch at the corresponding end and the associated directional relay 25 is energized, a stick circuit for each traffic following relay including a back contact of the associated directional relay, and a front contact of each traffic following relay interposed in the stick circuit of the associated remote controlled relay in multiple with said front contact of the 30 associated directional relay.

2. Railway traffic controlling apparatus in combination with a stretch of track comprising, a signal at each end of the stretch for governing traffic into the stretch, a code controlled relay for 40 each signal effective when picked up to cause operation of the signal, a traffic locking circuit responsive to traffic conditions of the stretch and including a directional relay at each end of the stretch, means governed by each code relay when 45 operated to condition the traffic locking circuit for energizing the directional relay at the same end of the stretch, a stick circuit for each code relay including a front contact of the associated directional relay, a traffic following relay at each 50 end of the stretch energized when a train enters the stretch at the corresponding end, a stick circuit for each traffic following relay including a back contact of the directional relay located at the same end of the stretch, and a front contact 55 of each traffic following relay interposed in the stick circuit of the associated code relay in multiple with said front contact of the associated directional relay.

3. Railway traffic controlling apparatus in combination with a stretch of track comprising, a signal at each end of the stretch for governing trains into the stretch, a control relay for each signal provided with a remote controlled pick-up circuit and a local controlled stick circuit, a traffic locking circuit including the directional relay at each end of the stretch for selecting the direction of traffic, means governed by each control relay when picked up to condition the traffic locking circuit for energizing the directional relay at the same end of the stretch, a traffic following relay at each end of the stretch, means operated by a train entering the stretch to cause the directional relay and traffic following relay located at the end at which the

train enters to be respectively deenergized and energized, front contacts of the directional relay and traffic following relay interposed in multiple in the stick circuit of the associated control relay, and another contact interposed in the stick circuit 5 of each control relay which is operated in response to a train entering the stretch at the corresponding end, whereby a control relay is released when a train enters the stretch and may be reenergized by the remote controlled pick-up 10 circuit and retained energized by its stick circuit for operating the signal for a following train.

4. Railway traffic controlling apparatus comprising, a stretch of railway track formed with a detector track circuit at each end, a track relay 15 for each track circuit, a signal at each end of the stretch for governing trains entering the stretch, a control relay for each signal provided with a code controlled pick-up circuit and a stick circuit, a traffic locking circuit including a directional relay at each end of the stretch for selecting the direction of traffic, means controlled 20 by each control relay when picked up to condition the traffic locking circuit for energizing the directional relay at the same end of the stretch, a traffic following relay at each end of the stretch, means controlled by each track relay when shunted to deenergize the associated directional relay and to energize the associated traffic following relay, a front contact of each 25 track relay interposed in the stick circuit of the associated control relay to release the control relay when a train enters the section, and front contacts of the directional and traffic following relays at each end interposed in multiple in the 30 stick circuit of the associated control relay to 35 protect against a hidden lockout condition.

5. Railway traffic controlling apparatus comprising a stretch of railway track formed with a detector track circuit at each end, a track relay 40 for each track circuit, a signal at each end of the stretch for governing trains into the stretch, a control relay for each signal provided with a remote controlled pick-up circuit and a stick circuit, a traffic locking circuit including a slow 45 release directional relay at each end of the stretch for selecting the direction of traffic, means controlled by each control relay when picked up to condition the traffic locking circuit for energizing the directional relay at the same 50 end of the stretch, a traffic following relay at each end of the stretch, a front contact of each track relay interposed in the locking circuit to deenergize the selected directional relay when a train enters the stretch, a pick-up circuit of each 55 traffic following relay including a back contact of the associated track relay and a front contact of the associated directional relay, a stick circuit for each traffic following relay including a back contact of the associated directional relay, and two branch paths for the stick circuit of each 60 control relay one of which serially includes front contacts of the associated track and directional relays and the other of which includes a front contact of the associated traffic following relay. 65

6. Railway traffic controlling apparatus in combination with a stretch of double track railway having an eastbound track and a westbound track and each track of which is provided with automatic signals for governing traffic in the 70 normal direction of traffic comprising, a crossover located at one end of the stretch, a signal located adjacent the crossover to govern trains over the eastbound track in the normal direction of traffic with the crossover set in one position and to 75

govern trains over the westbound track against traffic with the crossover set in its other position, a manually operable control unit, means governed jointly by said unit and by said one position of the crossover to operate the signal as a semi-automatic signal, and other means governed jointly by said unit and said other position of the crossover to operate the signal as a manual block signal.

10 7. Railway traffic controlling apparatus in combination with a stretch of double track railway having a crossover at one end of the stretch and the track on which traffic normally moves away from said one end through the stretch provided with automatic signaling apparatus comprising, a signal located adjacent the crossover to direct traffic to the track provided with automatic signaling apparatus when the crossover is set at one position and to direct traffic to the other track for movement through the stretch against traffic when the crossover is set at its other position, a manually operable control unit, means governed jointly by said unit and by said one position of the crossover to control the signal as a semi-automatic signal, and other means governed jointly by said unit and said other position of the crossover to control the signal as a manual block signal.

8. Railway traffic controlling apparatus in combination with a stretch of double track railway each track of which is provided with automatic signals for governing traffic in the normal direction of traffic, a crossover located at one end of the stretch comprising, a signal located adjacent the crossover to govern traffic into the stretch in the normal direction of traffic with the crossover set in one position and against traffic with the crossover set in its other position, a first and a second code controlled relay operatively connected with a remotely controlled coding unit located adjacent the crossover, means governed jointly by said first relay when selected by the coding unit and by said one position of the crossover to operate the signal as a semi-automatic signal, and means governed jointly by both of said relays when selected by the coding unit and by said other position of the crossover to operate the signal as a manual block signal.

9. Railway traffic controlling apparatus in combination with a stretch of double track railway each track of which is provided with automatic signals for governing traffic in the normal direction of traffic comprising, a pair of crossovers located at one end of the stretch, two signals one for each track located adjacent the crossover and each of said signals adapted to govern traffic into the stretch either in the normal direction of traffic or against traffic according to the position of the crossovers, control apparatus located adjacent the crossover manually operable from a remote station, means governed jointly by said control apparatus and said crossovers when the crossovers are positioned for trains to move to the track on which traffic moves from the crossovers in the normal direction of traffic for selectively operating the signals as semi-automatic signals, and other means governed jointly by said control apparatus and said crossovers when the crossovers are positioned for trains to move to the track on which traffic moves away from the crossovers against the normal direction of traffic for selectively operating the signals as manual block signals.

10. Railway traffic controlling apparatus in combination with a stretch of double track rail-

way each track of which is provided with automatic signaling apparatus for governing traffic in the normal direction of traffic comprising, a crossover located at one end of the stretch, a signal located adjacent the crossover to govern traffic into the stretch in the normal direction of traffic with the crossover set in one position and against traffic with the crossover set in its other position, a remote controlled coding unit located adjacent the crossover, a first code controlled relay and a call-on code controlled relay operatively connected with said unit, means governed jointly by said first relay and said one position of the crossover to operate said signal as a semi-automatic signal, means governed jointly by said two relays and said one position of the crossover to operate the signal as a call-on signal, and other means governed jointly by said two relays and said other position of the crossover to operate the signal as a manual block signal.

11. Railway traffic controlling apparatus in combination with a stretch of double track railway having a crossover at one end of the stretch and automatic signaling apparatus provided for the track on which traffic normally moves through the stretch from said one end comprising, a first signal located adjacent the crossover to direct traffic to the track provided with automatic signaling apparatus when the crossover is set at one position and to direct traffic to the other track for movement through the stretch against traffic when the crossover is set at its other position, a second signal located adjacent the other end of the stretch to direct traffic into the stretch on said other track, a traffic locking circuit responsive to traffic conditions of said other track, a remote controlled unit located at each end of the stretch for selective operation from a remote station, means governed by each unit when selected and said other track is unoccupied to condition the traffic locking circuit to establish traffic from the end of the selected unit and to control the associated signal, and means governed by said one position of the crossover to render the associated unit ineffective to condition the locking circuit and to cause the unit to control said one signal as a semi-automatic signal.

12. Railway traffic controlling apparatus in combination with a stretch of double track railway having a crossover at one end and automatic signaling apparatus provided for the track on which traffic normally moves through the stretch from said one end comprising, a signal located adjacent the crossover to direct traffic to the track provided with automatic signaling apparatus when the crossover is set at one position and to direct traffic to the other track for movement through the stretch against traffic when the crossover is set at its other position, a traffic locking circuit responsive to traffic conditions of said other track, two control units one at each end of the stretch and capable of being selectively operated from a remote station, means governed by each unit when operated to condition the locking circuit to establish traffic from the end of the operated unit, means governed jointly by the unit adjacent the crossover and said one position of the crossover to control the signal as a semi-automatic signal; means governed by the unit adjacent the crossover, said other position of the crossover and said locking circuit to control the signal as a manual block signal by establishing a clear manual block signal when said other track is unoccupied and a permissive manual block signal when said other track is occupied.

13. Railway traffic controlling apparatus in combination with a stretch of track provided with automatic signaling apparatus for governing traffic through the stretch in the normal direction of traffic comprising, a signal at each end of the stretch, a traffic locking circuit for the stretch including a directional relay at each end, two remotely controlled relays one at each end of the stretch and capable of selective operation from a remote station, means governed by each remote controlled relay when operated and the stretch unoccupied to condition the locking circuit for energizing the directional relay at the end of the operated remote controlled relay to establish traffic from that end, means controlled jointly by the directional and remote controlled relays adjacent the normal entrance end of the stretch to operate the corresponding signal as a semi-automatic signal, and means governed jointly by the directional and remote controlled relays adjacent the normal exit end of the stretch to operate the corresponding signal as a manual block signal.
14. Railway traffic controlling apparatus in combination with a stretch of double track rail-way having a crossover at one end of the stretch and the track on which traffic normally moves away from said one end through the stretch provided with automatic signaling apparatus comprising, a signal located adjacent the crossover to direct traffic to the track provided with automatic signaling apparatus when the crossover is set at one position and to direct traffic to the other track for movement through the stretch against traffic when the crossover is set at its other position, control apparatus located adjacent the crossover capable of operation from a remote station, means governed by said control apparatus to operate the signal as a semi-automatic signal when the crossover is set at said one position and as a manual block signal when the crossover is set at said other position, a first indication means responsive to said signal when operated as a semi-automatic signal to indicate at the remote station the position of the signal, and a second indication means responsive to the signal when operated as a manual block signal to indicate at the remote station the position of the signal.
15. Railway traffic controlling apparatus in combination with a stretch of double track rail-way having a crossover at one end of the stretch and the track on which traffic normally moves away from said one end through the stretch provided with automatic signaling apparatus comprising, a signal located adjacent the crossover to direct traffic to the track provided with automatic signaling apparatus when the crossover is set at one position and to direct traffic to the other track for movement through the stretch against traffic when the crossover is set at its other position, control apparatus located adjacent the crossover capable of operation from a remote station, means governed by said control apparatus to operate the signal as a semi-automatic signal when the crossover is set at said one position and as a manual block signal when the crossover is set at said other position, a first indication means responsive to said signal when operated as a semi-automatic signal to indicate at the remote station the position of the signal, and a second indication means controlled in part by said other position of the crossover to indicate at

the remote station the position of the signal when operated as a manual block signal.

16. Railway traffic controlling apparatus in combination with a stretch of double track rail-way having a crossover at one end of the stretch which is set at one position for movements into the stretch in the normal direction of traffic and is set at the other position for movements into the stretch against traffic comprising, a signal located adjacent the crossover to govern traffic into the stretch, control apparatus located adjacent the crossover capable of operation from a remote station, operating means governed jointly by said control apparatus and said other position of the crossover to operate the signal as a manual block signal, said means operative to establish a clear manual block signal when the stretch is unoccupied by a train moving against traffic and a permissive manual block signal for a second train moving against traffic, and indication means controlled by said operating means to indicate the clear and permissive positions of the signal at the remote station.

17. Railway traffic controlling apparatus in combination with a stretch of double track rail-way having a crossover at one end of the stretch which is set at one position for movements into the stretch in the normal direction of traffic and is set at the other position for movements into the stretch against traffic comprising, a signal located adjacent the crossover to govern traffic into the stretch, control apparatus located adjacent the crossover capable of operation from a remote station, a signal control relay and another relay effective when both are energized to cause the signal to display a clear signal and when said signal control relay is energized and said other relay is deenergized to cause the signal to display a permissive signal, means governed jointly by the control apparatus and said other position of the crossover to selectively energize said signal control relay and said other relay according to traffic moving through the stretch against traffic, and indication means governed by said signal control relay and said other relay to indicate the clear and the permissive positions of said signal at the remote station.

18. Railway traffic controlling apparatus in combination with a stretch of double track rail-way having a crossover at one end of the stretch which is set at one position for movements into the stretch in the normal direction of traffic and is set at the other position for movements into the stretch against traffic comprising, a signal located adjacent the crossover to govern traffic into the stretch, control apparatus located adjacent the crossover capable of operation from a remote station, a traffic locking circuit responsive to traffic conditions of the track on which movements are made from said crossover against traffic and including a directional relay effective when energized to establish movements against traffic, means governed by said control apparatus to condition the traffic locking circuit for energizing said directional relay, operating means controlled jointly by said directional relay and said control apparatus for operating the signal to either a clear or a permissive position, and indication means governed by the locking circuit to indicate at the remote station when a train occupies the stretch moving against traffic.
